PACKAGE AND METHOD OF PACKAGING

Michael J. Milmoe, Glen Ellyn, Ill., assignor to
 F. B. Redington Co., Chicago, Ill., a corpora-
 tion of Illinois

Application March 28, 1936, Serial No. 71,488

8 Claims. (Cl. 229—51)

This invention relates to a package for pack-
 aging an article and to the method of packaging
 an article.

The important object of the invention is to
 5 provide new and improved means for quickly and
 easily opening a package whereby the manual
 manipulation of a protruding tab will not only
 open the inner wrapper, but will also cause the
 tearing or cutting of the outer band or label
 10 whereby the contents of the package is instantly
 available after the tab has been pulled.

A further object of the invention is the provi-
 sion of a package for an article whereby the wrap-
 pings about the article is arranged in a certain
 15 predetermined order and arrangement so that the
 entire wrapper and the outer label or band may
 be instantly cut or torn by the manipulation of
 a protruding tab or member, to permit easy and
 ready access to the contents or article in the
 20 package.

Another object of this invention is the method
 of arranging a plurality of wrappers or bands
 about a package with a strip or tape arranged
 25 in a predetermined manner relative to the wrap-
 per and positioned in a certain way with respect
 to the outer band or label, so that the strip or
 tape may be operated to cut or tear or otherwise
 cause the wrapping elements to loosen or sever
 30 and thereby permit easy access to the contents
 of the package.

Numerous other objects and advantages will
 be apparent throughout the progress of the fol-
 lowing specification.

The accompanying drawing illustrates a se-
 lected embodiment of the invention and the views
 therein are as follows:

Fig. 1 is a detailed perspective view of a pack-
 age and embodying the invention, the outer band
 or label being omitted;

40 Fig. 2 is a detailed perspective view of the pack-
 age showing the outer band or label partly
 formed about the package;

Fig. 3 is a view similar to Fig. 2 showing the
 manner in which the outer band or label is ap-
 plied about the wrapper;

Fig. 4 is a detailed transverse sectional view
 on the line 4—4 of Fig. 1; and

Fig. 5 is a detailed perspective view of the com-
 pleted package.

50 Referring to the drawing, 10, Fig. 4, design-
 ates an article such as a piece of gum, confec-
 tion, or other article which is to be wrapped.
 About the article there is wound an opening strip
 or piece of tape 11. This tape commences at a
 55 point marked 12, Fig. 4, extends completely about

the article and has its outer end 13 protruding
 a predetermined distance beyond the end of the
 article, and forms an opening tab 14. A wrapper
 15, which may be of any suitable material such
 as tinfoil or waxed paper or both, extends com-
 pletely about the article 10 and is so arranged
 that the tape member 11 passes under the wrap-
 per 15 a predetermined distance. One end or
 edge 16 of the wrapper extends a predetermined
 distance inwardly beyond the end 12 of the tape 10
 11, while the outer free end 17 of the wrapper
 overlaps the end 16 of the wrapper but is short
 of the end 13 of the tape, Fig. 4. In other words,
 the inner end of the wrapper extends inwardly
 a predetermined distance beyond the inner end 15
 of the tape while the tape 13 extends between
 the free edge 17 of the wrapper and protrudes
 over a part of the wrapper and a predetermined
 distance beyond the edge 17, Fig. 4. The tape
 20 12 is fixed adhesively to the inside of the wrapper
 as indicated at 18, Fig. 4.

An outer band or label wrapper 19 extends
 about the package covering the article and its
 wrapper 15, but is so wound or entwined about
 the package so as to permit the tape 11 to extend 25
 beyond the edge of the band. The inner edge
 20 of the band 19 is on top or around the wrapper
 15 and extends below the tape 12, as clearly
 shown in Fig. 4. The tape 11, where it passes
 over the edge 20 of the band 19 is inclined or 30
 humped as indicated at 21. This hump is caused
 by the tape extending over an additional thick-
 ness of the material. The outer edge 22 of the
 band 19 extends substantially to the end of the
 package and over the tape 11, but short of the 35
 end 13 of the tape. Therefore, when the tab
 14 is pulled, the outer band 19 will be loosened
 because the tape 11 extends under the band 19
 and under the wrapper 15. Continued manual
 manipulation of the tab 14 causes the wrapper 40
 15 to be released. Inasmuch as the tape 11 is
 stuck to the inside of the wrapper 16 as indicated
 at 18, the tape 11 can not be merely slid out from
 under the wrapper. Pulling of the tab 14, there-
 fore, will cause the outer label band and the 45
 inner wrapper to be loosened, or the tape will
 cause the outer band and the inner wrapper to
 be torn or cut. Therefore, the manipulation of
 the tab 14 will permit opening or cutting of the
 outer wrappings to permit ready and easy access 50
 to the article.

In packaging a confection, and particularly
 in packaging chewing gum, it is desirable that
 the package be as airtight as possible. There-
 fore, the tucks and flaps carry an adhesive and 55

where adhesive is used and the flaps and tucks are relatively tight and stuck, the tape 11 causes a tearing action completely about the article thereby permitting the article to be readily slipped out of the package.

The invention provides, therefore, simple and inexpensively means for permitting easy access to the article by causing the outer label band and the inner wrapper to be instantly and quickly removed upon merely pulling a free tab which extends a predetermined distance beyond the edge of the package.

If it is preferred that the tab do not come into immediate contact with the article 10, a loose wrapper may be applied about the article and between the article and the tape.

In packaging the article the tape 11 is first applied about the article. The wrapper 15 is then placed over the tape so that its inner end 20 will be above the tape, while its outer end will be below the free end of the tape. The label band 19 is then placed about the package with one end under the protruding edge of the tape, as clearly shown in Fig. 3, and its outer free edge 25 22 over the tape, as clearly shown in Fig. 5.

The invention, therefore, contemplates a simple and convenient method of securely wrapping an article but permitting the wrappers to be released, cut or torn away by the mere pulling or 30 unwinding of a tape element which surrounds the article, but which is stuck or otherwise fastened to the enclosing wrapper. Furthermore, by arranging the tape between the edges of the outer label band, this latter band is also removed when 35 the tape is pulled or unwound. It may be said, therefore, that the invention contemplates the removal or tearing away of two separate wrappers by the mere unwinding or pulling of a single opening tape, part of which tape extends 40 beyond an edge of the package to provide an opening tab.

Changes may be made in the form, construction and arrangement of the parts, and the method may be varied to certain degrees, without departing from the spirit of the invention 45 or sacrificing any of its advantages, and the right is hereby reserved to make all such changes as fairly fall within the scope of the following claims.

The invention is hereby claimed as follows:

1. A package for articles comprising an opening member extending substantially once only about an article and having a protruding portion to form a tab, an inner wrapper extending under one part of the member and over another part 55 thereof, and an outer wrapper extending about the package, the outer wrapper having its free edges overlapped, the protruding portion extending between the lapped edges of the outer wrapper.

2. A package for articles comprising a tape member extending substantially once only about an article, a first wrapper about the article and extending under one part of the tape and over another part thereof, a second wrapper extending about the article over the first wrapper, said second wrapper having its ends overlapping, said tape having a free end extending between the said overlapping ends of said second wrapper.

3. A package for articles comprising an inner 70 wrapper arranged about an article and having its opposite edges overlapping, an opening mem-

ber about the article having its inner end fastened to said wrapper and its other end arranged between the overlapped edges of the wrapper and extending a predetermined distance beyond said overlapped edges, and an outer wrapper about 5 said inner wrapper and having its edges overlapping, said opening member extending substantially directly from said first named overlapped edges between the lapped edges of the outer wrapper whereby both the wrappers will be cut 10 or torn by the opening member when it is manually operated.

4. The method of packaging an article which consists in applying an opening element and an inner wrapper about an article with the ends of 15 the wrapper in overlapped relation, arranging the end of the opening element between said overlapped wrapper ends, placing an outer wrapper about the inner wrapper and package with its ends also in overlapped relation, and arranging 20 the end of the opening element between the overlapped ends of the outer wrapper.

5. A package for articles comprising an inner wrapper arranged about an article with its ends in overlapping relation, an opening tape arranged 25 within said wrapper, one end of the tape extending outwardly between the overlapped ends of said wrapper and the tape being anchored to the inner side of the wrapper, and an outer wrapper arranged about the inner wrapper with its ends 30 in overlapping relation but offset with respect to the overlapped ends of the inner wrapper, the first named tape end also extending between the overlapped ends of the outer wrapper.

6. A package for articles comprising an elongated opening member extending about the article, a first wrapper about the article and about the opening member and having its ends overlapping, the end of the opening member extending between the overlapped portions, and a second 35 wrapper extending about the article over the first wrapper, said second wrapper having its ends overlapping and having the said end of the opening member extending therethrough, the second named overlapped portions being offset 45 with respect to the first named overlapped portions with the opening member extending substantially directly from the one through the other and forming an exterior tab member.

7. A package for articles comprising an elongated opening member extending about the article, a first wrapper about the article and about the opening member and having its ends overlapping, the end of the opening member extending between the overlapped portions, and a second 55 wrapper extending about the article over the first wrapper, said second wrapper having its ends overlapping and having the said end of the opening member extending therethrough and freely beyond the edge of the package to form a gripping 60 device.

8. A package for articles comprising an opening member extending about an article and having a protruding portion to form a manually operable opening device, an inner wrapper extending under one part of the member and over another part thereof, and an outer wrapper extending about the package, the outer wrapper having its free edges overlapped, and the protruding portion of the opening member extending between 70 the lapped edges of the outer wrapper.

MICHAEL J. MILMOE.
